UNITED STATES PATENT OFFICE.

CHARLES M. FLINK, OF IRONWOOD, MICHIGAN.

CURTAIN STRETCHER.

Application filed October 14, 1927. Serial No. 226,194.

The present invention is concerned with the provision of a curtain stretcher including a rectangular stretching framework which is capable of ready and accurate adjustment to 5 accommodate curtains of varying widths and lengths, and which is so constructed that the frame members will be accurately squared in all positions of adjustment, and there is no possibility of distorting or mis-shaping a curtain while drying.

Other objects of the invention are to provide a curtain stretcher which may be conveniently set up, and which is self-supporting in its normal position of use.

Still other objects are to provide a device of this character of extremely simple, practical construction which will be rugged, durable and efficient in use, and well suited to the requirements of economical manufacture, 20 convenient manipulation and ready knock-down for purposes of compact storage or transportation.

With the above noted and other objects in view, the invention consists in certain novel 25 features of construction and combinations and arrangements of parts, as will be more fully hereinafter set forth and pointed out in the claims. The invention may be more fully understood from the following description in 30 connection with the accompanying drawings, wherein—

Fig. 1 is a view in front elevation of a curtain stretcher embodying the present invention.

Fig. 2 is a vertical sectional view on the line 2—2 of Fig. 1, the dotted lines indicating the positions of the prop and members as they are swung toward collapsed position.

Fig. 3 is an edge view of one of the vertically disposed side frame members.

In the drawings I have used the reference numerals 10, 10 to designate a pair of spaced supporting legs for the stretching frame. Props 11 are hingedly connected at 12 to the 45 rear faces of the legs 10 near the upper ends of the latter, and may be swung rearwardly to the full line position of Fig. 2. To aid in sustaining the legs in their normal rearwardly inclined position, the structure is reinforced by brace bars 13 pivoted at 14 to the legs 10 near the lower ends of the latter, and detachably engageable with the lower ends of the 50 props 11 as by the slot and pin connection 15.

The curtain stretching frame includes an 55 upper horizontally disposed frame member 16 detachably secured to the legs 10, a lower

horizontally disposed frame member 17 adjustable on the legs 10, and a pair of side frame members 18 connecting the upper and lower frames or stringers 16, 17.

In order to assure accurate positioning of the upper frame or stringer 16 at exactly right angles to the legs 10, 10, I employ a construction which is substantially equivalent to a T-square and which includes right angularly disposed stop members 19 on the legs 10 against which the lower edge of the upper stringer 16 rests. The stringer may be detachably secured to the legs in abutting relation to the members 19 by the use of screws 20 and wing nuts 21. Preferably, sufficient play is left at the screws to accommodate for shrinkage of the wooden legs and stringer.

The lower stringer 17 is maintained in parallelism with the upper stringer by the use 75 of screws 22 working in vertical slots 23 in the legs 10. The lower stringer may be clamped in any desired position of vertical adjustment on the legs by tightening wing nuts 24 which coact with the screws 22, and bind the lower stringer against the legs.

The side frame members 18 are provided with spring hooks 25 at their upper ends adapted to straddle and snugly embrace the upper stringer. Additional hooks or spring 85 fingers 26 are carried by slide members 27 which work up and down on the side frames 18. The hooks 26 are adapted to embrace the lower stringer 17. Slides 27 are of course designed to permit engagement of the lower 90 stringer by the hooks 26 in any position of adjustment of the stringer.

In order to assure accurate positioning of the side frames 18 they are formed with slots 28 and 29 engageable respectively with any 95 one of a series of pins 30 and 31 carried by the upper and lower strings 16, 17.

These pins are adapted to secure the curtains which are being stretched or dried, and similar rows of pins 32 are provided on the 100 side frame members.

In order that the adjustable stretcher frame may be accurately pre-adjusted to accommodate any sized curtain, the upper and lower stringers are graduated as seen in the 105 drawings, and graduations are also provided either on the side frame members or on the front faces of the legs 10.

From the foregoing description it will be 110 apparent that the entire device may be conveniently knocked down for purposes of storage or shipment, and when set up, will define

a true rectangular frame adjustable throughout any desired range of curtain sizes.

Various changes and alterations might be made in the general form and arrangement 5 of the parts described without departing from the invention. Hence I do not wish to limit myself to the details set forth, but shall consider myself at liberty to make such changes and alterations as fairly fall within 10 the spirit and scope of the appended claims.

I claim:

1. A curtain stretcher including a supporting frame having means for supporting it in an inclined position, and an adjustable 15 stretcher frame detachably mounted thereon, the stretcher frame including an upper horizontal stringer fixed to the supporting frame, a lower horizontal stringer slideable on the supporting frame and a pair of parallel transverse frame members adjustable along the stringers having their 20 ends projecting beyond the frame, and a pair of parallel transverse frame members adjustable along the projecting ends of the stringers.

2. A curtain stretcher including a supporting 25 frame and an adjustable stretcher frame detachably mounted thereon, the stretcher frame including an upper horizontal stringer fixed to the supporting frame, a lower horizontal stringer slideable on the supporting frame and a pair of parallel transverse frame members adjustable along the stringers, the 30 last mentioned frame members including

fixed spring hooks adjacent their upper ends to engage the upper stringer, and spring fingers to engage the lower stringer, said fingers being carried by slides mounted on the members.

3. A curtain stretcher including a supporting frame and an adjustable stretcher frame detachably mounted thereon, the stretcher frame including an upper horizontal stringer fixed to the supporting frame, a lower horizontal stringer slideable on the supporting frame and a pair of parallel transverse frame members adjustable along the stringers, curtain retaining pins on the stretcher frame, the transverse frame members of the stretcher frame having slots therein, each slot receiving a pin of the stringers.

4. A curtain stretcher comprising a pair of legs, a prop hinged to the upper end of each leg, a brace connecting the legs and props, an upper stringer secured to the upper ends of the legs with its ends projecting beyond the legs, a lower stringer, means for adjustably securing the lower stringer to the legs with its ends projecting beyond the legs, a pair of transverse members, and means for detachably and adjustably securing said members to the projecting ends of the stringers.

Signed at Ironwood in the county of Gogebic and State of Michigan this 10th day of October A. D. 1927.

CHARLES M. FLINK.
